DIAPHRAGM FOR LOUDSPEAKERS

BACKGROUND OF THE INVENTION

The present invention relates to a diaphragm for a loudspeaker made of foamed plastic or like material.

Heretofore a number of types of diaphragm made of foamed plastic such as foamed polystyrene or like material have been proposed. FIGS. 1 A, B, C, D and E illustrate some examples of such diaphragm. FIG. 1A shows a diaphragm made of a flat plate 1a having uniform thickness of foamed plastic material such as foamed polystyrene and having a voice coil 2a attached to its central portion. FIG. 1B shows a diaphragm made of a flat plate 1b having a thickness increasing stepwise toward its central portion to which a voice coil 2b is attached. FIG. 1C shows a diaphragm made of a flat plate 1c having a thickness increasing gradually toward its central portion to which a voice coil 2c is attached. FIG. 1D shows a diaphragm made of a plate 1d having uniform thickness which is formed in a cone having an apex portion to which a voice coil 2d is attached. FIG. 1E shows a diaphragm made of a flat plate 1e which is formed at its central area in a gradually curved conical form, to which a voice coil 2e is attached.

These diaphragms can faithfully reproduce low frequency sounds and their frequency characteristics in the low frequency range depend on piston motion or on overall bending (fundamental single bending) motion of the diaphragm. However, in the medium or high frequency ranges, the diaphragms tend to produce divided vibrations, resulting in peaks and dips in their frequency characteristics. Consequently, a smooth frequency characteristic such as in a conventional cone-type loudspeaker using a cone paper diaphragm cannot be obtained in these diaphragms. Furthermore, these diaphragms have relatively increased mass at the central portion, so that they cannot satisfactorily reproduce higher frequency sounds.

SUMMARY OF THE INVENTION

It is an object of the present invention to provide a diaphragm for a loudspeaker made of foamed plastic or like material which can reproduce effectively high frequency sounds as well as low frequency sounds.

It is another object of the present invention to provide a diaphragm for a loudspeaker made of foamed plastic or like material in which a flat or smooth frequency characteristic curve can be obtained throughout whole range from low frequency to high frequency.

In accordance with the present invention there is provided a diaphragm for a loudspeaker made of foamed plastic or like material in which the diaphragm has a decreased thickness at its central portion to which a voice coil is attached.

BRIEF DESCRIPTION OF THE DRAWINGS

FIGS. 1 A, B, C, D and E are sections showing examples of a conventional loudspeaker diaphragm;

FIGS. 2, 3, 4 and 5 are sectional views showing several embodiments of the diaphragm according to the present invention.

DESCRIPTION OF THE PREFERRED EMBODIMENT

FIGS. 2, 3, 4 and 5 illustrate some embodiments of the present invention.

FIG. 2 shows a first embodiment in which a diaphragm is made of a flat plate 3a of foamed plastic material which has a decreased thickness at its central portion 4a, to which a voice coil 5a is attached. The diaphragm shown in FIG. 2 can reproduce high frequency sound, but has some defect in that it lacks rigidity at the central portion so that deep dips may occur in the frequency characteristic in its low frequency range.

FIG. 3 shows a second and most preferred embodiment of

the present invention in which a diaphragm is made of a flat plate 3b which is formed in a gradually curved conical shape so as to gradually increase its rigidity at its central area. In this central area the plate 3b gradually decreases its thickness toward the central portion 4b to which a voice coil 5b is attached, thereby decreasing mass of effective vibrating area which contributes to the vibration of the diaphragm at high frequency range.

FIG. 4 shows a third embodiment of the present invention, 10 in which a diaphragm is made of a flat plate 3c of foamed plastic or like material which is formed in a gradually curved conical shape at its central area, as in the embodiment shown in FIG. 3. The plate 3c has a thick part 6 at the peripheral portion of the conical area where the angle of inclination is relatively small, said thick part 6 serving to increase the rigidity of the plate to improve the frequency characteristics in the low frequency range. The plate 3c gradually decreases its thickness from the thick part 6 toward a central portion 4c where the angle of inclination is increased, to which a voice 15 coil 5 is attached. In such a construction, the plate has a relatively high rigidity in the central portion owing to its conical shape although the thickness is decreased toward the central portion, so that characteristic in the low frequency range is not adversely affected by the decrease of the thickness. 20 Furthermore, while the level in medium frequency range generally tends to be increased by forming the plate in the conical shape, excessive increase in level is prevented owing to the increase of vibrating mass in the medium frequency range by the thick part 6. Thus a relatively flat or smooth 25 characteristic curve can be obtained through low frequency sound to high frequency sound.

FIG. 5 shows a fourth embodiment of the present invention in which a diaphragm is made of a flat plate 3d of foamed plastic material, which has a free edge 7 at its periphery, 30 through which the plate is supported by a frame (not shown). A central portion 4d of the plate has similar construction as shown in FIG. 3, and a voice coil 5d is attached to said central portion.

The following table shows two examples of the diaphragm 40 constructed in accordance with the present invention.

	Size of diaphragm	Thickness at periphery	Thickness at central portion
45	800 × 500mm	7mm	3mm
	400 × 320mm	3mm	2mm

Of course, the thickness may be above description determined, depending on the size of the diaphragm, the material of the diaphragm or the desired characteristics.

50 It will be understood from the above-description that in accordance with the present invention sounds can be effectively reproduced throughout whole range from low frequency to high frequency with a flat or smooth frequency characteristic, by a diaphragm made of foamed plastic or like material which could not heretofore give a flat frequency characteristic.

I claim:

1. In a diaphragm for a loudspeaker, said diaphragm comprising a member the major portion of which is substantially planar and of substantially uniform thickness foamed plastic 60 and said diaphragm having a voice coil attached thereto, the improvement which comprises providing in the central portion of said member an indentation of curved conical shape, the angle of inclination of the walls of said conical indentation with respect to the diaphragm axis gradually increasing as the apex of the conical shape is approached, the walls of said curved conical indentation having a peripheral portion adjacent to and thicker than said major portion and then gradually decreasing in thickness toward said apex, and said voice coil being attached to said apex.
